UNITED STATES PATENT OFFICE.

WILLIAM ORR, OF TRENTON, NEW JERSEY, ASSIGNOR TO THE NEW JERSEY WIRE CLOTH COMPANY, OF SAME PLACE.

FIREPROOF CONSTRUCTION.

SPECIFICATION forming part of Letters Patent No. 644,940, dated March 6, 1900.

Application filed September 6, 1898. Serial No. 690,317. (No model.)

To all whom it may concern:

Be it known that I, WILLIAM ORR, a citizen of the United States, residing at Trenton, county of Mercer, and State of New Jersey, 5 have invented certain new and useful Improvements in Fireproof Constructions, fully described and represented in the following specification and the accompanying drawings, forming a part of the same.

10 This invention relates to an improved fireproof construction adapted especially for use as a combined floor and ceiling construction, the object of the invention being to provide a construction having improved fireproof 15 qualities and providing the required floor-support, while employing but a small body of concrete or similar plastic material.

The invention relates especially to an improved fireproofing of the webs and flanges of 20 the beams, to an improved floor-support, and to an improved metal joist and holding-clip construction, but includes also various other features of construction.

As a full understanding of the invention 25 can best be given by an illustration and detailed description of constructions embodying the same, such a description will now be given in connection with the accompanying drawings, forming a part of this specification, and 30 showing constructions embodying all the features of the invention in their preferred forms, and the features forming the invention will then be particularly pointed out in the claims.

In the drawings, Figure 1 is a section of a 35 complete floor and ceiling construction, the section being taken transversely to the floor-beams and showing a construction with the concrete web between the upper portions of the beams. Fig. 2 is a section on the line 2 40 of Fig. 1 with the fireproofing and lathing omitted from a portion of the beam to show the construction. Fig. 3 is a view similar to Fig. 1, showing my improved floor-support construction with concrete web between the 45 lower portions of the beams. Fig. 4 is a view similar to Fig. 2, taken on the line 4 of Fig. 3. Fig. 4^a shows the preferred arrangement of the joists in plan view. Fig. 5 is a section longitudinally of the beam, showing a girder- 50 fireproofing in connection with the construction shown in Fig. 3. Fig. 6 is a view similar

to Fig. 1, showing a form of construction employing curved joists. Fig. 7 is a view similar to Fig. 6, showing another form of curved-joist construction with a separate ceiling. 55

Referring now particularly to Figs. 1 and 2, A are the floor-beams, which are shown as of the common I form, upon the upper flanges of which are supported joists B, shown as formed of thin metal bars extending from 60 beam to beam and arranged edgewise vertically, these joists being provided on their ends with notches which receive the flanges of the beams and clips α thereon, the portions of the joists below the notches forming 65 tongues 10, entering openings 1 in the clips below the flanges of the beams, so that the joists B are thus held in position on edge and the tongues 11 above the flanges resting on the tops of the clips and serving to strengthen 70 the joists at the end and aid in holding the clips α in place on the beam-flanges. The joists B thus extend above and below the top flanges of the beams, and on the under side of the joists B is secured in any suitable manner, so as to be supported thereby, reticulated 75 metal, which is shown as common woven-wire lathing C, but which may be of any suitable form and size of openings between the parts of the reticulated metal, either of woven or 80 netted wire or metal rods or straps or perforated or expanded metal, so that the concrete or similar plastic material applied from above will set into the spaces between the parts of the lathing and secure an anchorage 85 to prevent thrust against the joists B and the beams A. The lathing C is shown as secured to the joists B by wire ties 2 at suitable 90 intervals; but other means of attachment may be used or the lathing supported in any other suitable manner. The lathing C preferably 95 extends downward around the bottoms of the beams, so as to inclose the latter and be offset from the bottoms of the beams sufficiently to provide fireproofing of the entire beams by 100 a body D of concrete or similar plastic material applied from above and forced down around the web or webs of the beams, so as to form a single continuous body of fireproof material extending about the entire beams and forming fireproofing below the beams 105 and extending above the tops of the beams

and joists, so as to form a fireproof floor upon which the board or other flooring E may be applied, either directly or on wood or other joists F, as shown. With the joists 5 B and metallic lathing applied as shown the filling of concrete D may be applied from above without the use of a centering below the lathing, so that the concrete will key through the openings between the parts of 10 the lathing and secure an anchorage of the concrete in the lathing and a proper base for the plastic ceiling, the metallic parts of the construction being sufficient to hold or to support the concrete while setting. It will 15 be understood, however, that a suitable centering may be used in producing this construction, if desired for any reason.

The construction shown in Fig. 1 is complete in itself and may be used without plaster 20 finish; but it is preferably finished by applying on the under side of the lathing C the usual plaster ceiling G, so that the entire floor and ceiling construction is formed with a single body of concrete or similar plastic 25 material embedding the joists and fireproofing the beams throughout, with the plaster ceiling applied directly thereon.

While I prefer to apply the concrete or 30 similar plastic material so as to cover the beams entirely and fireproof the webs and lower flanges of the beams, as shown at the left in Fig. 1, and this feature forms a part of the invention, this fireproofing of the webs and bottoms of the beams by the concrete 35 may be omitted, while employing other features of the invention, and an air-space left about the webs and bottoms of the beams, as shown at the right of Fig. 1, the plaster G on the under side of the lathing C then being 40 the only covering of the beams outside this air-space.

In Figs. 3 and 4 I have shown a construction in which the fireproofing of the webs and bottoms of the beam is secured by a body of 45 concrete or similar material, as in the construction shown in Fig. 1; but in this case the joists B are mounted on the lower flanges of the beams and a plain ceiling construction is formed instead of the dropped-beam construction 50 shown in Figs. 1 and 2. The joists B and clips x in this construction are the same as in the construction shown in Figs. 1 and 2, except that the joists and clips are applied to the bottom flanges of the beams, so that the joists extend below the beams, the 55 depth of these joists below the beams depending upon the amount of fireproofing desired on the under side of the beams. An air-space may be left below the beams, as at the 60 right in Fig. 1, if desired. The arrangement of the metallic lathing C and the application of the plaster G on its under side is the same as in the construction shown in Figs. 1 and 2. Above the joists B the concrete is filled in 65 only sufficiently to fully embed and protect the joists and secure the required strength in the body of concrete, and this construction

(shown in Figs. 3 and 4) thus provides a fireproof web between the lower portions of the beams, leaving a large air-space between 70 the web and the flooring. The webs and upper flanges of the beams are embedded in bodies of concrete D', extending along the sides of the beams above the concrete web D, so that the beams are fully protected, although 75 the concrete web is of less depth than the beams. A continuous air-space may be left between the web D and the flooring; but preferably this air-space will be divided and the floor supported by joists H, which are set 80 down into the space between the beams and bodies of concrete D', so as to rest upon the web D, preferably being inclined at the ends so as to be supported also by concrete D'. The construction shown is preferred, in which 85 the joists H are wooden joists extending over a series of beams and deeply notched on their under sides, so that their notched portions rest upon the tops of the beams and their lower edges extend down to the web D. 90 The joists may thus be supported wholly or largely by the tops of the beams. Instead of wooden joists, however, joists formed of fireproof blocks molded from suitable material may be used, being set down between the 95 beams and resting upon the web D. Upon the joists H is supported the flooring E, either directly or on studding, as desired. This construction, with the concrete web between the lower portions of the beams and the floor-supporting joists thereon, will be found very 100 efficient, while it is very simple and cheap and may be produced very rapidly.

The construction shown in Figs. 1 to 4 and above described may be used with the metal 105 joists B arranged at equal distances apart throughout, so as to form rectangular bodies of concrete between them; but I preferably arrange these joists, substantially as shown in Fig. 4^a, with the opposite ends of adjacent 110 joists at different distances from each other, so as to form wedge-shaped bodies of concrete between successive joists, the spaces between the joists and ends of the concrete blocks along each beam thus being alternately 115 wide and narrow. This construction secures much greater strength, as the wedge form of the concrete blocks between the joists effectively prevents any tendency to slip transversely to the beams and relieves largely the 120 sidewise thrust upon the beams. The joists B may be used without spanners; but the use of spanners is preferred, as a stronger construction is thus secured and the joists B may 125 thus be placed in position more rapidly and with greater accuracy in spacing the joists, which is especially desirable in the construction shown, in which the opposite ends of the joists are spaced differently. As shown in Fig. 4^a, spanners are used formed of looped 130 metal rods or straps 8, passed over the tops of the joists and connected by spanner-rods 9, hooked through eyes in the rods or straps 8. In Fig. 5 I have shown the construction of

Figs. 2 and 3 applied in connection with a fire-proofed metal girder, the girder being fire-proofed throughout and on its under side by the same continuous body of concrete or similar plastic material by which the beams A are fireproofed. In this construction the girder I, to which the beams A may be secured by angle-plates, as shown, or in any other suitable manner, is fireproofed as follows: 5 Rods 12 extend between adjacent beams A on opposite sides of the girder, according to the thickness of concrete desired, and are hooked over the bottom flanges of the beams, so as to be carried thereby, and about these rods 10 rods 12 are hooked at intervals rods 13, which extend downward to a distance below the girder-flange depending on the thickness of fire-proofing desired for the bottom of the girder and are then bent inward and upward and 15 hooked over the bottom flange of the girder, so as to be supported thereon, these rods 12 being placed at suitable intervals apart and the rods 12 on opposite sides of the girders being shown as secured together by wire ties 4, so as to hold them in position on the girder-flange. The metallic lathing C below the beams A is then continued downward and around the under side of the girders, being secured to and held in position by these rods 20 25 30 35 40 45 13, so as to form a body of fireproof material extending about and below the girders and continuous with the concrete floor and beam fireproofing, the plaster ceiling then being applied on the outside of the lathing in this part of the construction in the same manner as below and between the beams A. This girder protection with the rods and lathing may also be used without the concrete filling, so as to form an air-space about the webs and below the flanges of the girders, as shown and previously described in connection with the beam A at the right of Fig. 1, or the space below the flange may be filled with previously-molded blocks of fireproof material held in place by the rods 13.

In long spans it may be desirable to use curved joists to strengthen the floor against deflection under heavy weight, and such curved joists may be notched and supported 50 from the bottom flanges of the beams in the same manner as shown in Figs. 1 to 4 or in any other suitable manner. In Figs. 6 and 7, however, I have shown constructions employing such curved joists with the fireproofing of the webs and bottom flanges of the beams by the floor concrete, but with the curved joists supported by different means from that shown in Figs. 1 to 4 and from a point above the beam-flange, which is practicable with deep beams.

In the construction shown in Fig. 6 the joists B support the lathing C and the floor and ceiling in the same manner as previously described, but are supported from the beams 55 60 65 A either by hangers 14 from the tops of the beams, these hangers being slotted or looped, so as to receive the ends of the joists, as shown

at the left of Fig. 6, or by supports 15, resting on the bottom flanges of the beams and notched at the top to receive the joists B, as 70 shown at the right of Fig. 6. The supports for the lathing C, below the flanges of the beams A in this construction, are secured by metal rods 16, arranged at suitable intervals apart and bent to proper form to seat on the 75 lower flanges of the beams and extend below the beams the required distance and upward to the joists B, so as to hold the lathing properly and at the required distance from the beams, in accordance with the thickness of 80 fireproofing desired, separate rods 16 on opposite sides of the beams being preferably used, as shown, and tied together below the beams by wire ties 4 in the same manner as shown in Fig. 5 in connection with the girders I. In this construction the concrete D is 85 shown as extending only to the tops of beams; but this is not essential, and the concrete may extend above the beams.

In Fig. 7 I have shown a construction in 90 which similar curved joists B are used, being supported from the tops of the beams by hangers 17, separate hangers being used on opposite sides of the beams and slotted or provided with side loops to support the ends 95 of the joists, these hangers 17 extending downward below the bottoms of the beams and then inward to the center of the beams, where they are provided with eyes 5, through which the ceiling-supporting rods 18 are passed and secured under the proper tension by nuts 6, these rods 18 supporting the ceiling-lathing K and ceiling-plaster G. In this construction the body of concrete or similar plastic material D fills the space above the lathing C, secured on the under side of the joists B and the space within the lathing supported by the hangers 17 about the webs and below the bottoms of the beams A, so as to provide a continuous body of fireproofing material, forming the floor and protection about the webs and bottoms of the beams.

The arrangement of the joists so as to form wedge-shaped blocks of concrete, as shown in Fig. 4^a and previously described in connection with the construction shown in Figs. 1 and 2, is applicable also to the constructions shown in Figs. 6 and 7. These curved joists also may be used in place of the straight joists in the construction shown in Figs. 3 and 4 100 105 110 115 120 and supported from the bottom flanges of the beams in the same or any suitable manner. A curved dropped beam-ceiling construction may thus be formed or a level suspended ceiling may be used.

The features forming the invention may be embodied in constructions differing in detail from those shown, and it will be understood that the claims are not to be limited to the exact form or arrangement of parts illustrated.

What I claim is—

1. The combination with beams, of joists formed of metal plates extending from beam

to beam and supported on their edges, reticulated metal extending between the beams and below the bottoms of the beams with space between the reticulated metal and the beams, 5 and a filling of concrete or similar plastic material between the beams in which the joists are completely embedded, substantially as described.

2. The combination with beams, of joists 10 formed of metal plates extending from beam to beam and supported on their edges, reticulated metal extending between the beams and below the bottoms of the beams with space between the reticulated metal and the beams, 15 and a continuous body of concrete or similar plastic material between the beams and filling the space between the reticulated metal and the beams and in which the joists are completely embedded, substantially as de- 20 scribed.

3. The combination with beams, of joists 25 formed of metal plates extending from beam to beam and supported on their edges, reticulated metal extending between the beams be- 30 low the joists and under the bottoms of the beams with space between the reticulated metal and the beams, and a filling of concrete or similar plastic material applied upon the reticulated metal between the beams and in 35 which the joists are embedded, substantially as described.

4. The combination with beams, of joists 35 formed of metal plates extending from beam to beam and supported on their edges, reticulated metal extending between the beams be- 40 low the joists and under the bottoms of the beams with space between the reticulated metal and the beams, and a continuous body of concrete or similar plastic material applied upon the reticulated metal and embedding the joists and filling the space between the reticulated metal and the beams, substan- 45 tially as described.

5. The combination with floor-girders and 45 beams extending transversely to the girders, of joists formed of metal plates extending from beam to beam and supported on their edges, reticulated metal extending between the beams and around the bottoms of the 50 beams and girders with space between the reticulated metal and the beams and girders, and a continuous body of concrete or similar plastic material applied upon the reticulated metal and filling the space about the webs of the beams and girders and between the reticulated metal and the bottoms of the beams 55 and girders, substantially as described.

6. The combination with floor-girders and 60 beams extending transversely to the girders, of joists formed of metal plates extending from beam to beam and supported on their edges, reticulated metal extending between the beams below the joists and extending about the bottoms of the beams and girders 65 with space between the reticulated metal and the beams and girders, and a continuous body of concrete or similar plastic material applied

upon the reticulated metal and embedding the joists and filling the space about the webs of the beams and girders and between the reticulated metal and the bottoms of the beams and girders, substantially as described. 70

7. The combination with flanged beams, of joists formed of metal plates extending from beam to beam and provided with notches at 75 their opposite ends to receive the flanges of the beams whereby the joists are supported on their edges and extending above and below the beam-flange, reticulated metal below the joists extending between the beams and 80 around the bottoms of the beams with a space between the reticulated metal and beams, and concrete or similar plastic material applied upon the reticulated metal and embedding the joists, substantially as described. 85

8. The combination with flanged beams, of joists formed of metal plates extending from beam to beam and provided with notches at 90 their opposite ends to receive the flanges of the beams whereby the joists are supported on their edges and extending above and below the beam-flange, reticulated metal extending between the beams and around the bottoms of the beams, and a continuous body 95 of concrete or similar plastic material applied upon the reticulated metal and embedding the joists and filling the space about the webs of the beams and between the reticulated metal and the bottoms of the beams, substan- 100 tially as described.

9. The combination with flanged beams, of joists formed of metal plates extending from beam to beam and provided with notches at 105 their opposite ends to receive the flanges of the beams whereby the joists are supported on their edges and extending above and below the beam-flange, reticulated metal below 110 said joists, and a filling of concrete or similar plastic material applied upon the reticulated metal and in which the joists are embedded, 115 substantially as described.

10. The combination with flanged beams, of joists formed of metal plates extending from beam to beam and provided at their opposite ends with notches receiving the bottom flanges 115 of the beams whereby the joists are supported on their edges and extend below the beams, reticulated metal below the joists extending from beam to beam and below the bottoms of the beams, and concrete or similar plastic ma- 120 terial applied upon the reticulated metal and in which the joists are embedded, substan- 125 tially as described.

11. The combination with flanged beams, of joists formed of metal plates extending from 125 beam to beam and provided at their opposite ends with notches receiving the bottom flanges of the beams whereby the joists are supported on their edges and extend below the beams, reticulated metal below the joists extending 130 from beam to beam and below the bottoms of the beams, and concrete or similar plastic ma- 135 terial applied upon the reticulated metal to form a web between the beams embedding the

joists and extending along the beams to fire-proof the webs and upper flanges of the beams, substantially as described.

12. The combination with flanged beams, of 5 joists formed of metal plates extending from beam to beam and notched on their edges to receive the beam-flanges whereby the joists are supported on their edges, said joists being arranged to form wedge-shaped spaces between 10 the joists, the successive spaces tapering in opposite directions, reticulated metal extending between the beams, and a filling of concrete or similar plastic material applied upon the reticulated metal and forming 15 wedge-shaped bodies between the joists, substantially as described.

13. The combination with beams, of joists extending between the lower portions of the beams and formed of metal plates supported 20 on their edges, reticulated metal between the beams, concrete or similar material applied on said metal to form a fireproof web extending between the lower portions of the beams and embedding the joists, and floor-supporting 25 joists extending from beam to beam and dividing the air-space above the web, substantially as described.

14. The combination with beams, of joists extending between the lower portions of the 30 beams and formed of metal plates supported on their edges, reticulated metal between the beams, concrete or similar material applied on said metal to form a fireproof web extending between the lower portions of the beams 35 and embedding the joists and extending along the beams to fireproof the webs and upper flanges of the beams, and floor-supporting joists extending between the fireproofing of the beam-webs and dividing the air-space 40 above the concrete web, substantially as described.

15. The combination with beams, of joists extending between the lower portions of the beams and formed of metal plates supported 45 on their edges, reticulated metal between the beams, and concrete or similar material applied on said metal to form a fireproof web extending between the lower portions of the beams and embedding the joists and extending 50 along the beams to fireproof the webs and upper flanges of the beams, substantially as described.

16. The combination with a beam-flange, of clip α thereon having a depending portion 55 provided with opening 1 and a plate-joist having tongue 10 entering said opening to support the plate on its edge, substantially as described.

17. The combination with a beam-flange, 60 of clip α thereon having a depending portion provided with opening 1 and a plate-joist having tongue 10 entering said opening below the flange and tongue 11 above the flange, substantially as described.

18. The combination with a beam-flange, 65 of clip α thereon having a depending portion

provided with opening 1 and a plate-joist having tongue 10 entering said opening below the flange and tongue 11 above the flange resting on the clip, substantially as described. 70

19. The combination with the beams A, of plate-joists B notched at their ends to receive the beam-flanges, reticulated metal between the beams, and a filling C of concrete or similar material in which the joists are completely 75 embedded, substantially as described.

20. The combination with the beams A, of plate-joists B notched at their ends to receive the beam-flanges, reticulated metal between the beams and extending around the bottoms 80 of the beams, and a filling of concrete or similar material between the beams and around the webs and bottoms of the beams, substantially as described.

21. The combination with the beams A, of 85 plate-joists B notched at their ends to receive the bottom flanges of the beams, reticulated metal between the beams, a web of concrete or similar material D between the beams embedding the joists, and floor-supporting joists 90 H extending from beam to beam and resting on the web D, substantially as described.

22. The combination with the beams A, of plate-joists B notched at their ends to receive the bottom flanges of the beams, reticulated 95 metal between the beams, a web of concrete or similar material D between the beams embedding the joists, fireproofing D' extending along the webs and upper flanges of the beams, and floor-supporting joists H extending between the fireproofing D' and resting on the web D, substantially as described. 100

23. The combination with the beams A, of plate-joists B notched at their ends to receive the bottom flanges of the beams, reticulated 105 metal between the beams, a web of concrete or similar material D between the beams embedding the joists and fireproofing D' extending along the webs and upper flanges of the beams, substantially as described. 110

24. The combination with the beams A, of a web of concrete or similar material D extending between the lower portions of the beams, and floor-supporting joists H extending from beam to beam and resting on the web 115 D, substantially as described.

25. The combination with the beams A, of a web of concrete or similar material D extending between the lower portions of the beams and bodies of concrete or similar material D' extending along the webs and upper 120 flanges of the beams, and floor-supporting joists H extending between the concrete D' and resting on the web D, substantially as described. 125

26. The combination with the beams A, and fireproof web D between the lower portions of the beams, of the floor-supporting joists H extending over a series of beams and notched to rest upon the tops of the beams and on web 130 D, substantially as described.

27. The combination with the beams A and

girders I, of rods 12 supported by the beams, supports 13 depending from the rods 12 and extending about the girder-flange, and reticulated metal on said supports, substantially as 5 described.

28. The combination with beams A and joists B, of supports 16 extending downward from the joists and beneath the beam-flanges and seated on the beam-flanges and reticu-

lated metal on said supports, substantially as 10 described.

In testimony whereof I have hereunto set my hand in the presence of two subscribing witnesses.

WILLIAM ORR.
